HERMAN E. WHITING, OF PALMYRA, NEW YORK.

PRIMER FOR GAS-ENGINES.

1,171,159.

Specification of Letters Patent. Patented Feb. 8, 1916.

Application filed February 6, 1911. Serial No. 606,939.

To all whom it may concern:

Be it known that I, HERMAN E. WHITING, of Palmyra, in the county of Wayne and State of New York, have invented a new and useful Improvement in Primers for Gas-Engines, which improvement is fully set forth in the following specification, and shown in the accompanying drawings.

The present invention relates to internal combustion engines, and it has for an object to make provision whereby a thorough mixing of the explosive mixture used in starting the engine takes place prior to its introduction into the cylinders of the engine.

Another object of the invention is to provide for the automatic admission of air to the explosive mixture whenever the speed of the motor reaches a certain limit.

To these and other ends the invention consists in certain parts and combinations of parts all of which will be hereinafter described, the novel features being pointed out in the appended claims.

In the drawings: Figure 1 is a side view of a priming cup with an automatic air valve; Fig. 2 is a section on the line *a—a* of Fig. 1; and Fig. 3 is a sectional view through a mixer for the explosive mixture with the priming cup and the air valve shown in vertical section on the line *b—b* of Fig. 2.

In carrying out the invention there is arranged in the connection between the carbureter and the cylinders a mixer which so acts on the explosive mixture that the free particles of gasoline are thoroughly vaporized. The mixer *per se* is not claimed in this application, but it may be generally described as comprising a casing 1 having an intake 2 and a discharge 3. Within the casing is arranged a baffle against which the inflowing mixture contacts, the free particles of gasoline adhering to the baffle and the vaporized mixture passing the baffle.

The baffle in this instance comprises two cone shaped members 4 and 5, the former being imperforate and located in proximity to the intake 2, while the member 5 is perforated and is of larger diameter than the member 4. A pin 6 holds the members 4 and 5 in spaced relation, and mineral wool, asbestos, or other incombustible fibrous material 7 is arranged between the members 4 and 5. An annular chamber 8 may be arranged around the intake 2 to collect gasoline and other impurities, and the baffle is

held firmly in the casing against a seat 9 by a coil spring 10, which facilitates the removal of the baffle for cleaning purposes.

Arranged to deliver into the connection between the carbureter and the engine cylinders is a primer which connects with the mixer on the inflowing side of the baffle. The primer in this instance comprises a cup 11 and a lateral screw threaded extension or nipple 12, which engages internal threads in a bore leading to the chamber 8, the cup being connected to the nipple by a passageway 11^a. The liquid from the cup may be controlled by a turn plug 13 held to its seat by a spring 14 and adapted to be operated by a handle 15.

In order that air may be admitted into the gas conductor between the carbureter and the cylinder to mix with the priming charge, the primer casing may be provided with an air supply 16 leading into the passageway 11^a between the nipple and the turn plug, the air supply being controlled by an automatically opening valve 17 which, in this instance, is in the form of a ball held to its seat 18 by a helical spring 19. The seat 18 may be arranged in an externally threaded sleeve 20 which is adjustable in the primer casing to vary the pressure of the spring 19 on the valve 17, a nut 21 serving to hold the sleeve 20 in its adjusted position.

In using the invention the cup 11 receives the priming gasoline and discharges the same into the chamber 8. On cranking or otherwise starting the engine, air is drawn through the automatically opening air valve and mixes with the primer gasoline, the baffle impeding the progress of the mixture until the gasoline is thoroughly vaporized. The air valve in addition to vaporizing the priming charge may be adjusted so as to open only at certain times, as when the engine is making high speed or climbing hills.

With this invention, the starting of the engine is effected by a high grade mixture and it is unnecessary, therefore to ignite the charge sometime before the piston of the engine reaches the end of its compression stroke. Furthermore, greater efficiency is secured in the engine after the starting for the reason that air is admitted to the mixture whenever a high speed of the engine is reached.

The air is admitted automatically into the connection between the carbureter and the

engine cylinders so that during the normal running of the engine, the latter depends upon the mixture as discharged from the carbureter but, upon high speeds, a sufficient amount of air is automatically admitted to give a leaner mixture. This air mingles with the mixture as the mixture ascends within the connection and thoroughly mixes with the mixture before the engine cylinders are reached. It is also advantageous to admit a priming fluid in the vertical connection because the fuel spreads and the ascending air vaporizes the fuel before the cylinders are reached. It will be noted that, after the valve 13 is opened to permit the fuel to discharge from the cup or container 11, the fuel runs into the chamber 16 located below the cup 11. Upon the closing of the valve 13, the motor is operated to draw air past the valve 17 causing the fuel to be vaporized and carried into the mixer where it is still further vaporized.

What I claim as my invention and desire to secure by Letters Patent, is—

1. The combination with a gas engine having a plurality of cylinders, and a carbureter, of a connection between the carbureter and the cylinders extending in an upward direction from the carbureter, one wall of said connection being provided with a threaded opening, and an automatic air valve having a threaded nipple fitted in said threaded opening, said valve being adjusted to remain closed at slow speeds of the motor and opening automatically on high speeds to act on the mixture after the latter is discharged by the carbureter, and a priming chamber connected with the air valve to discharge the fuel by way of the threaded nipple of the air valve.

2. A combined primer and air supply for gas engines comprising a casing having an externally-threaded nipple and a fuel cup formed integrally therewith, the fuel cup

projecting upwardly and the nipple projecting horizontally, a turning plug arranged in horizontal alinement with the nipple and in vertical alinement with the cup and having a port adapted to connect the cup and the nipple when in one position, said casing also having a valve chamber communicating with said nipple independently of the cup and having a normally closed check valve therein.

3. A combined primer and air supply for gas engines comprising a casing having an externally threaded nipple and a fuel cup formed integrally therewith, the fuel cup projecting upwardly and the nipple projecting horizontally, a turning plug arranged in said casing in horizontal alinement with the nipple and in vertical alinement with the fuel cup, said casing also having an integral portion depending below the nipple and communicating with the nipple, a valve seat adjustable on said depending portion, a ball valve arranged in said depending portion and coöperating with said seat, and a spring operating on the ball valve and housed by said depending portion.

4. A combined primer and air supply for gas engines comprising an externally threaded nipple, a fuel cup, the fuel cup projecting upwardly and the nipple projecting horizontally, a turning plug arranged to connect or disconnect the fuel cup with the nipple, a chamber also having connection with the nipple, a valve seat adjustable in said chamber from the exterior thereof, a ball valve coöperating with the seat, and a helical spring arranged within said chamber and bearing against the ball valve.

HERMAN E. WHITING.
